US00D701637S

(12) **United States Design Patent**
Xue et al.

(10) **Patent No.:** US D701,637 S
(45) **Date of Patent:** ** Mar. 25, 2014

(54) **LED LAMP CUP**

- (71) Applicant: **Civilight Shenzhen Semiconductor Lighting Co., Ltd.**, Shenzhen (CN)
- (72) Inventors: **Xinshen Xue**, Shenzhen (CN); **Youzhi Yuan**, Shenzhen (CN)
- (73) Assignee: **Civilight Shenzhen Semiconductor Lighting Co., Ltd.**, Shenzhen (CN)
- (**) Term: **14 Years**
- (21) Appl. No.: **29/457,051**
- (22) Filed: **Jun. 6, 2013**

(30) **Foreign Application Priority Data**

Dec. 6, 2012 (CN) 2012 3 0605738

- (51) **LOC (10) Cl.** **26-99**

(57) **CLAIM**

The ornamental design for an “LED lamp cup,” as shown and described.

DESCRIPTION

FIG. 1 is a perspective view of the LED lamp cup;
FIG. 2 is a front view of the LED lamp cup;
FIG. 3 is a rear view of the LED lamp cup;
FIG. 4 is a left side view of the LED lamp cup;
FIG. 5 is a right side view of the LED lamp cup;
FIG. 6 is a top view of the LED lamp cup; and,
FIG. 7 is a bottom view of the LED lamp cup.

1 Claim, 4 Drawing Sheets
